UNITED STATES PATENT OFFICE.

ADOLF MÜLLER DEUTSCHMANN, OF ELTVILLE, GERMANY.

WINDOW-FRAME.

1,021,181.

Specification of Letters Patent. Patented Mar. 26, 1912.

Application filed May 31, 1911. Serial No. 630,349.

To all whom it may concern:

Be it known that I, ADOLF MÜLLER DEUTSCHMANN, a subject of the Emperor of Germany, residing at Eltvile-on-the-Rhine, 5 Germany, have invented Improvements in Window-Frames, of which the following is a specification.

The present invention relates to frames such as used for windows, doors and the like, 10 and more particularly to the type of glass frames used in gardens and the like for the protection and forcing of plants. It is known to make such frames either of iron or wood. The iron frames have the advantage of being durable, but they are at the same time heavy and, being good heat-conductors, they tend to maintain a uniform 15 temperature at both sides of the frame. The wooden frames are light and also bad heat-conductors, but are detrimentally affected by moisture and therefore of little durability. It is also known to make frames out of metal plate formed with a channel 20 for the reception of a wooden mass.

According to the present invention the frame is made of solid wooden laths onto which a jacket of metal plate is tightly 25 pressed.

The invention is illustrated in the accompanying drawings by a perspective cross-sectional view of a lath such as used for plant protecting frames.

The frame is made of solid wooden laths 30 *b* onto which a jacket *a* of galvanized iron-plate is pressed so as to fit tightly on the wood and prevent access of air and moisture to the same. At the side or sides of

the lath adjoining the glass panes *d*, the metal plate is bent to form a ledge *g* for supporting the panes. The edges *c* of the 40 metal plate are joined and lapped, the seam being disposed near the ledge *g* so as to be covered by the putty *f* used for securing the panes to the frame. In this manner a loosening of the seam as well as an entrance 45 through the seam of moisture, will be effectively prevented by the putty. The upper surfaces of the laths are preferably channeled, as shown in the figure, such channelling serving on the one hand to strengthen 50 the frame and on the other hand to provide means for collecting and discharging the water during showers of rain.

A frame constructed in this manner will be both light and strong. It will also be 55 of great durability since the wood is protected by the plate jacket against moisture. At the same time the frame has a low degree of heat-conductivity and does not therefore tend to equalize the temperatures 60 prevailing at the opposite sides thereof.

I claim:—

Window and like frames composed of wooden laths covered entirely by metal plate, 65 said plates being bent to form ledges for the reception of the glass panes, the edges of the plate being lapped, the seam being disposed so as to be covered by the putty which secures the panes to the frame, substantially as set forth.

ADOLF MÜLLER DEUTSCHMANN.
